UNITED STATES PATENT OFFICE.

CALE J. SCHNEIDER, OF TOLEDO, OHIO, ASSIGNOR TO THE DE VILBISS MANUFACTURING COMPANY, OF TOLEDO, OHIO, A CORPORATION OF OHIO.

DESIGN FOR A SPRAY HEAD FOR ATOMIZERS.

Application filed July 31, 1922. Serial No. 3,255. Term of patent 14 years.

To all whom it may concern:

Be it known that I, CALE J. SCHNEIDER, a citizen of the United States, and a resident of Toledo, in the county of Lucas and State of Ohio, have invented a new, original, and ornamental Design for a Spray Head for Atomizers, of which the following is a specification, reference being had to the accompanying drawings, forming a part thereof.

In the drawing Figure 1 is a top plan view of a spray head showing my new design applied to an atomizer bottle illustrated in dotted lines, and Fig. 2 is a side elevation thereof.

I claim:—

The ornamental design for a spray head for atomizers, substantially as shown.

CALE J. SCHNEIDER.
